UNITED STATES PATENT OFFICE.

ALBERT P. OLMSTEAD, OF TROY, ASSIGNOR OF ONE-HALF TO ALEXANDER T. PORTER, OF WEST TROY, NEW YORK.

HUB-ATTACHING DEVICE.

SPECIFICATION forming part of Letters Patent No. 394,876, dated December 18, 1888.

Application filed July 3, 1888. Serial No. 278,922. (No model.)

To all whom it may concern:

Be it known that I, ALBERT P. OLMSTEAD, a resident of the city of Troy, in the county of Rensselaer and State of New York, have 5 invented certain new and useful Improvements in Hub-Attaching Devices; and I do hereby declare that the following is a full, clear, and exact description of the invention, that will enable others skilled in the art to 10 which it appertains to make and use the same, reference being had to the accompanying drawings, and to the letters of reference marked thereon, which form a part of this specification.

15 Similar letters refer to similar parts in the several figures therein.

My invention relates to improvements in hub-attaching devices; and it consists of the novel construction and combination of parts 20 hereinafter described, and pointed out in the claims.

Figure 1 of the drawings is a central longitudinal section of a vehicle-wheel box, inclosed axle-spindle, and attaching devices. Fig. 2 is 25 a plan view of the axle-spindle detached. Figs. 3 and 4 are respectively plan and end views of the wheel-hub box detached. Figs. 5 and 6 are respectively end and side views of the spindle-inclosing sleeve. Figs. 7 and 8 are 30 respectively end and side views of the interiorly-threaded retaining sleeve or collar. Fig. 9 is an interior end view of the box-flange and lock-screw detached from the box and thimble. Fig. 10 is a side view of the lock-screw 35 detached from all other parts.

The invention which comprises the subject-matter of this application is an improvement upon the construction shown and described in my prior application, Serial No. 267,340, filed 40 March 16, 1888, to which reference may be had.

A represents the axle-spindle, and B the box, which is inserted in the wheel-hub B' (shown by dotted lines) in the usual manner.

The axle may have dust-excluding flanges 45 A² and a longitudinal lubricant-receiving groove, A³. The end of the spindle is reduced in diameter to form the shoulders a and b, the portion reduced to the smaller diameter being threaded at its end, as shown. A thimble, C, 50 interiorly threaded at its outer end and pro-

vided interiorly with the interiorly-projecting annular flange C', is slipped upon the smaller end of the spindle in such a manner that its inner end finds a bearing upon the shoulder b and the inner side of its flange a bearing 55 upon the shoulder a. The sleeve or collar D, interiorly threaded and having wrench-notches D', is then screwed upon the threaded part of the spindle, passing within the outer end of the thimble until its inner end finds a 60 bearing upon the outer side of the thimble-flange, substantially as shown in Fig. 1, and all substantially as described in my said prior application, except that, as therein shown and described, the thimble was exteriorly instead 65 of interiorly threaded, and the outer ends of the thimble, collar, and spindle were about flush with each other. The hub was secured to the thimble by a cap-nut, which screwed onto the thimble and at the same time upon 70 the hub.

In my improved device I provide the hub, or the box B, inserted therein, with an annular interiorly-projecting flange, d. The inner diameter of this flange is the same as that of 75 the thimble C, and the flange is threaded interiorly and correspondingly with the thimble. The flange may be integral with the box, or it may be provided with an interiorly-threaded sleeve, d', adapted to be screwed 80 onto the correspondingly exteriorly-threaded end of the box, as shown in Fig. 1. The lock-screw S is adapted to fit both the thimble and the box-flange and be screwed therein, as shown in Fig. 1. The screw has an oil-chamber, S³, opening interiorly, and is provided with a flange, S', adapted to engage with the box-flange.

The spindle is prepared for receiving the hub and box by slipping the thimble C to 90 place and screwing the collar D upon the threaded end of the spindle, as before explained. The hub and box, provided with the flange d, are then slipped upon the axle-spindle to the desired position and securely locked 95 therein by screw S, screwed into the flange and the thimble, as shown in Fig. 1. To prevent the thimble from revolving while the screw is being inserted in it, I make it exteriorly of an octagonal or other angular form, 100

as shown in Figs. 5 and 6, and make the interior of the hub or box of corresponding form, as shown in Fig. 4 at B².

By having a considerable number of plane 5 sides the wheel can be slipped onto the axle and thimble in almost any position.

The position of the hub relatively to the axle can be adjusted by adjusting the position of the screw in the box-flange before it 10 enters the thimble.

The screw may have a projecting rectangular head, as shown by dotted lines e in Fig. 1, adapted to be turned by a wrench, or it may have a screw-driver slot, S².

15 To remove the hub from the axle, it is only necessary to unscrew the lock-screw until it is withdrawn from the thimble, whereupon the hub can be slipped off or onto the axle.

It will be observed that the thimble and 20 screw turn with the box and hub, the inner end of the thimble and side of the thimble-flange bearing upon the spindle-shoulders b and a. When these parts wear away to become loose, they can easily be readjusted to 25 tighten them by screwing the collar D farther onto the spindle, or removing the collar and inserting between it and the thimble a washer of the desired thickness, at the same time advancing the lock-screw the same distance 30 through the flange d before it enters the thimble, whereby the relative position of the box and hub remains unchanged, or by varying the adjustment of the screw the relative position of the box can be changed as desired

to compensate for wear. The lock-screw is 35 provided with a flange, S', which is forced into engagement with the flange d and draws the threads upon the flange and screw into such close engagement as to effectually lock the parts which connect the box and thimble and 40 prevent their relative displacement.

What I claim as new, and desire to secure by Letters Patent, is—

1. In a hub-attaching device, the combination, with an interiorly-threaded thimble 45 secured to revolve upon the axle and a hub revolvable with said thimble and provided with an interiorly-projecting flange threaded to correspond with the threaded part of the thimble, of a lock-screw threaded to correspond 50 with and fit the threads of the thimble and hub or box flange, substantially as described.

2. In a hub-attaching device, the combination, with a thimble secured to revolve upon the axle and having an angular exterior surface, of a thimble-inclosing hub-box having its inner inclosing-surface of a size and form to receive and fit the exterior angular surface of the thimble, and means for securing the thimble within the box, substantially as de- 60 scribed.

In testimony whereof I have hereunto set my hand this 21st day of June, 1888.

ALBERT P. OLMSTEAD.
